Primary Examiner — Ruth McInroy(74) *Attorney, Agent, or Firm* — Albert T. Wu; David L. Hoffman; Hoffman Patent Group(57) **CLAIM**

I claim the ornamental design for a protective helmet, as shown and described.

DESCRIPTION

FIG. 1. is an upper perspective view of the helmet;
 FIG. 2. is a lower perspective view thereof;
 FIG. 3. is a front view thereof;
 FIG. 4. is a rear view thereof;
 FIG. 5. is a right side view thereof;
 FIG. 6. is a left view thereof;
 FIG. 7. is a top view thereof; and,
 FIG. 8 is a bottom view thereof.
